SINK AND DRAINBOARD ASSEMBLY

Andrew H. Galley, York Mills, Toronto, Ontario, Canada, assignor, by mesne assignments, to Luxene, Inc., New York, N. Y., a corporation of Delaware

Application May 18, 1949, Serial No. 93,865
In Canada March 18, 1949

4 Claims. (Cl. 4—187)

1

The present invention relates to a sink structure and a sink bowl and drainboard assembly designed to facilitate the installation of the sink and to obtain important advantages and economies incident to the advanced design and structural features thereof. The advantages include an improved appearance with an uninterrupted or unbroken sink surface and added durability particularly at the junction of the sink with the drainboard deck surface or composition deck covering material when the latter is employed. It is importantly of a design which makes it practical for a small home owner to make his own installation thereby avoiding the cost of outside assistance, as the mode of installation is such as not to require the employment of a highly skilled artisan.

In the past most sink bowls have been made of enameled steel wherein the top flanges of the bowls have been of a thickness of from $\frac{1}{16}$ " and heavier. As a result it was generally unsatisfactory to have the flange of the bowl rest on the sink deck due to the thickness of the flange edge and the general practice therefor has been to install the bowls below the sink deck with the use of separable moldings between the flange of the bowl and the surface of the deck. In such installations to obtain satisfactory appearance, with properly closed seams for sanitation and water tightness, it has required the employment of 30 highly skilled workmen. Although many attempts were made to overcome the difficulties in producing satisfactory sink installations in an economical manner none, so far as I am aware, was entirely successful when carried into practice 35 commercially on an industrial scale.

In accordance with the present invention the referred to difficulties of installation and other disadvantages of prior art structures are overcome by the employment of a single piece sink bowl drawn or pressed from sheets of stainless alloy of relatively thin gauge, of approximately $\frac{3}{1000}$ of an inch in thickness. The bowl is formed with a marginal, horizontal flange at its upper edge and the extreme edge of the flange is ground or beveled to a degree sufficient to obtain a relatively smooth joining between the drainboard deck surface and the flange when installed with the flange bearing directly on the upper surface of the deck. In further accordance with the invention the integral bowl flange is employed as the marginal molding and further as a clamping means for the rigid attachment of the sink to the

2

drainboard in conjunction and in cooperation with an improved and simplified securing means. The improved securing means comprises metal straps secured, as by welding or brazing, to the outer vertical surfaces of the bowl and provided with apertures to receive the ends of special clamping bolts. The bolts are fitted with threaded adjusting nuts adapted to apply a clamping pressure against the under side of the drainboard desirably through interposed washers so as to effectively secure the sink assembly.

In the simplified arrangement of the invention the bowl or basin flange is of substantial width or projection thereby to eliminate the requirement of other and separable molding. The method of assembling permits the flange to function as a clamping means in the securing of the sink by the special bolting arrangement. Moreover, as a further result of the substantial projection of the flange, it permits of a desirable degree of tolerance in the cutting of the drainboard opening thus to permit of a satisfactory assembly by relatively unskilled labor. I have discovered that these desirable results are obtainable in the manner as hereinafter more fully described by the employment of a unitary sink formed of stainless alloys of such characteristics as to be of adequate strength when made of the required relatively light gauge sheet metal.

An object of the invention is to produce an improved sink structure particularly adapted to facilitate assembly of the bowl with a drainboard or deck to permit of obtaining an improved assembly without the requirement of highly skilled labor therefor.

A further object of the invention is to produce an improved single piece sink bowl structure adapted to facilitate its installation without the requirement of a separable molding to effect a satisfactory joining with a supporting deck surface.

Another object of the invention is to provide a single piece sink bowl formed with an integral molding flange adapted to function as a clamping element in the assembling with a deck support in cooperation with an improved clamping bolt assembly to facilitate a satisfactory installation and of pleasing appearance.

The invention further contemplates a sink bowl and drainboard assembly comprising a single piece bowl formed with a marginal horizontal flange at its upper edge and drawn from a sheet of relatively thin stainless alloy and provided

with depending metal straps formed with apertures for securing bolts having threaded shanks for the reception of securing nuts positioned to exert a clamping pressure on the under side of the drainboard or supporting deck for securing of the bowl with the flange thereof overlying an upper surface of the supporting deck.

Other objects and advantages will become apparent from the following description taken in conjunction with the accompanying drawings in which:

Fig. 1 is a perspective view of the sink structure made in accordance with the present invention and inverted in position on the drainboard or deck of a sink installation as a preliminary step in the assembly operation;

Fig. 2 is a similar view with the sink or bowl removed after the tracing of the outline of the bowl for location on the deck and having dotted line indication for the cutting of an opening through the deck for the reception of the bowl or sink;

Fig. 3 is a perspective view of the supporting cabinet with the finished opening in the deck for the reception of the bowl and with the latter shown in position to be lowered into its assembled relation;

Fig. 4 is a view of the sink structure of the present invention showing the bowl in side elevation and assembled within the opening of the sink deck which is shown in broken section;

Fig. 5 is an exploded view in side elevation of the special clamping bolt and associated nut and washer elements;

Fig. 6 is a vertical sectional view of a portion of the improved bowl structure assembled with the drainboard for support and wherein the drainboard has a deck covering of linoleum or the like; and

Fig. 7 is a detailed vertical section view of a portion of an assembly employing a composition deck covering which is scarfed or countersunk to produce a flush joint connection with the flange of the bowl or sink.

Generally speaking the present invention contemplates the provision of a sink or bowl of single piece construction formed by drawing or pressing sheet metal of relatively light gauge and which may desirably be a corrosion resistant alloy such as the alloy known under the trade-mark of "Monel" or other suitable corrosion resistant metal alloy such as a nickel-chromium-iron alloy. It further contemplates an improved structural design and arrangement wherein the unitary sink bowl is formed with a horizontally extending upper marginal flange adapted in the assembly to provide an integral molding finish and to further function in cooperation with a special clamping bolt arrangement for rigidly clamping of the sink to a supporting deck and within an opening cut therethrough.

A preferred embodiment of the features of the invention is shown in the drawings wherein like reference numerals are applied to corresponding parts in the several views. As shown therein 1 indicates a suitable cabinet structure supporting the drainboard or deck 2, which may be of wood as customarily made, and is provided with a cut out opening 3 for the reception and positioning of the sink bowl 4 to be assembled therewith.

In carrying the invention into practice it is preferred to make the sink or bowl as a single piece of metal such as by drawing or pressing a sheet of corrosion resistant alloy metal of a

relatively light gauge to form the sink or bowl having substantially vertical side and end walls 6 and 7 and a bottom wall 8 provided with the usual downwardly flanged drain opening 9. The bowl is further formed at its upper edge with a continuous marginal horizontal flange 10 integral with the side and end walls and desirably of a thickness of about $\frac{3}{1000}$ of an inch. This flange 10 as shown, is of a width or outward extension from the side and end walls to provide for a substantial projection outwardly from the walls so as to provide a continuous or finished molding of pleasing appearance. The flange 10 by overlying engagement with the upper surface of the deck 2 at the framing of the opening provides support for the bowl and affords a means to contribute to the clamping of the bowl for rigid installation. As a result of its substantial width or projection from the body of the bowl the arrangement permits of a wide tolerance in the formation of the deck opening without impairing the security of and appearance of the final assembly.

As best shown in Figs. 4, 5, and 6 a simplified and effective means for securing or clamping the bowl element to the drain or deck board is provided. This securing means as shown is composed of metal straps 12 secured, as by welding or brazing, to the side and end walls of the sink member and provided with projecting lower ends formed with apertures 13 for the reception of clamping bolts. The clamping bolts 14, shown in Fig. 5, are of a special form having horizontally turned end portions 15 provided with notches 16 on their under sides adapted for positioning and retaining of the bolt ends within the apertures 13 of the straps 12. The upper end portions of the bolts are threaded at 17 for the adjustable support of internally threaded nuts 18. The nuts 18 are vertically adjustable thereon to produce clamping pressure against the under side of the deck by engagement therewith through interposed washers or bearing elements 19 having centrally positioning bosses 20 fitted to the central opening of the nut.

As best shown in Figs. 4 and 6 the straps 12 of the clamping means are formed of relatively thin sheet metal which permits of their being passed through the drainboard opening in the assembling of the bowl with the supporting deck 2. As will be noted, the inward extension 15 of the clamping bolt is projected inwardly through the aperture 13 of the straps to provide a bearing thereon in such manner that the resulting clamping pressures are applied to the straps vertically and lengthwise of the straps whereby the pressures are resisted by the metal on edge. This gives added strength and rigidity to the fastening and with reduced danger of loosening of the strap elements.

The simplicity and facility of installing the improved sink bowl and drainboard assembly will be best understood by reference to Figs. 1, 2 and 3.

As illustrated in Fig. 1 the sink bowl is placed upside down upon the sink drainboard or deck 2 in the position of its desired location and a pencil line is drawn on the deck using the outer edge of the flange 10 as a guide. The bowl is then removed and as illustrated in Fig. 2, a cutting line may then be drawn about one-half inch within the guided line and is indicated as a dotted line 22 for the purpose of contact. The opening 3 in the deck is then cut on the line 22. The bowl 4 is then placed in the deck opening, the clearance be-

ing such as to permit passage of the strap elements 12 permitting the bowl to be lowered substantially flush with the top surface of the deck and with the flange 10 of the bowl providing a rest bearing by overlying the marginal edge surface of the opening 3 as best shown in Fig. 4. The clamping means, composed of the bolts 14, adjusting nuts 18 and washers 19 are then assembled with the straps 12 by inserting the horizontal bolt portions 15 within the apertures and in seating registration with the notches. After this, as will be understood, the nuts 18 are turned to a degree sufficient to obtain the desired clamping pressure, through the interposed washer 19 against the under side of the deck, so as to rigidly clamp the bowl in its assembled position. As here shown the basin or bowl is generally rectangular in contour and is provided with two of the securing straps 12 on each side surface but it will be understood that the number of metal straps employed may be varied depending on the size of the bowl and the amount of pressure required to pull the flange of the bowl to a tight seal on the upper deck surface. Also, as will be appreciated a suitable cementing compound of a waterproof nature may be applied between the basin flange and the upper surface of the deck in the making of the assembly.

While in the Fig. 4 illustration the basin is shown supported and clamped in position by direct engagement with the upper surface of the drainboard it will be understood this may be modified by the employment as shown in Fig. 6 of a drainboard 2 having a composition surfacing material such as a linoleum deck layer 23 in which instance the flange 10 of the sink will bear directly upon the deck composition surface.

While as described the relative thinness of the light gauge metal of the flange 10 provides a molding joint between the bowl and drainboard, which is substantially flush with the surface of the latter, a fully flush construction may be obtained as shown in Fig. 7 by scarfing or countersinking the composition deck material at the marginal edge of the opening 3 and of a depth to receive the flange 10 so that its upper surface coincides with and is in the plane of the upper surface of the composition.

It is to be observed that the present invention provides a unitary type of sink bowl of special design to simplify installation in a sink and drainboard assembly and adapted to permit its successful installation without the requirement of highly skilled labor. It is, moreover, of a structural arrangement which permits of effecting a very satisfactory joint between the bowl and the deck surface without the employment of separable molding and one wherein the integral flange of the bowl provides a molding connection of a desirable and pleasing appearance. The invention structure further provides simple and effective means operative in conjunction with the bowl flange, for rigidly clamping of the sink bowl in its assembled position and in a manner which permits of its being readily removed for replacement of the deck surface when desired.

Although the present invention has been described in conjunction with preferred embodiments, it is to be understood that modifications and variations may be resorted to without departing from the spirit and scope of the invention as those skilled in the art will readily understand. Such modifications and variations are considered to be within the purview and scope of the invention and appended claims.

I claim:

1. An sink bowl unit formed of a corrosion-resistant alloy and provided with an integral marginal outwardly projecting flange of about $\frac{1}{1000}$ " thickness at its upper edge adapted to overlie the marginal edge portion defining a sink deck opening and provided with metal straps secured to the bowl in position to pass through the opening and having portions projecting from the under side thereof and adjustable securing means engaging the projecting portions and an under surface of the sink deck adapted in cooperation with the flange rigidly to secure the bowl in position, said securing means comprising bolts having threaded upper end portions and inturned lower end portions having notched under sides and adjusting nuts threaded to the bolt upper ends.
2. A sink and drainboard assembly comprising a unitary sink bowl formed of a pressed sheet of corrosion-resistant alloy, said drainboard being provided with an opening conforming to and slightly larger than the body of the bowl to receive the bowl positioned within the opening, said bowl being formed with an integral, continuous, horizontal flange projecting outwardly from its upper edge in position to overlie the drainboard edge surface defining the opening and said bowl having vertically positioned metal straps secured to its outer surface to project from the under side thereof and positioned to pass through the drainboard opening and adjustable securing means engaging an under surface of the drainboard and comprising bolts extending inwardly to engage the strap projections for clamping of the bowl in position in cooperation with the overlying flange.
3. A sink and drainboard assembly comprising a unitary sink bowl formed of a corrosion-resistant alloy, said drainboard being provided with an opening conforming to and slightly larger than the body of the bowl to receive the bowl positioned within the opening, said bowl being formed with an integral, continuous, horizontal flange projecting outwardly from its upper edge in position to overlie the margin edge surface defining the drainboard opening and said bowl having vertically positioned metal straps secured to its outer surface and having apertured portions projecting from the under side thereof, said straps being positioned to pass through the drainboard opening and adjustable clamping bolts having threaded nuts positioned to apply pressure against the under surface of the drainboard and having inwardly extending notched end portions engaging the strap projections within the apertures for clamping of the bowl in position in cooperation with the overlying flange.
4. A sink and drainboard assembly comprising a unitary sink bowl formed of a corrosion-resistant alloy, said drainboard being provided with an opening conforming to and slightly larger than the body of the bowl to receive the bowl positioned within the opening, said bowl being formed with an integral, continuous, horizontal flange projecting outwardly from its upper edge in position to overlie the margin edge surface defining the drainboard opening and said bowl having vertically positioned metal straps secured to its outer surface and having apertured portions projecting from the under side thereof, said straps being positioned to pass through the drainboard opening and adjustable clamping bolts having threaded nuts positioned to apply pressure against the undersurface of the drainboard and having inwardly extending notched

end portions engaging the strap projections within the apertures for clamping of the bowl in position in cooperation with the overlying flange, and washer elements interposed between the nuts and the drainboard and formed with bosses fitted to the bore of the nut for the positioning of the washers.
